UNITED STATES PATENT OFFICE.

HARRY S. HART, OF CHICAGO, ILLINOIS, ASSIGNOR TO NATIONAL DUMP CAR COMPANY, OF CHICAGO, ILLINOIS, A CORPORATION OF MAINE.

GENERAL-SERVICE RAILWAY-CAR.

1,300,958.

Specification of Letters Patent. Patented Apr. 15, 1919.

Application filed October 14, 1918. Serial No. 257,928.

To all whom it may concern:

Be it known that I, HARRY S. HART, a citizen of the United States, residing at Chicago, in the county of Cook and State of Illinois, have invented certain new and useful Improvements in General-Service Railway-Cars, of which the following is a specification.

This invention relates to general service 10 railway cars.

As is well known, the general service type of railway car is a car having a level floor extending from end to end of the car and being largely composed of hinged doors arranged to drop to discharge the load from 15 the car.

These cars are commonly constructed with the entire floor composed of the drop doors. It is apparent that in substituting for the 20 ordinary stationary floor of a gondola or other flat bottom car, a floor composed of drop doors, no advantage can be taken of the floor as a shock and strain resisting element.

25 The shocks and strains must, therefore, be transmitted wholly through the underframe members or through the sides of the car, or both. As railroad cars are subjected to severe racking strains, it is necessary in this 30 type of car to make provision to resist such strains.

It has been sometimes the practice, therefore, in building general service cars, to make a portion of the car floor extending inwardly from the end sills stationary with the remainder of the horizontal floor composed of drop doors. This, while adding to the stiffness of the car, necessitates shoveling out a portion of the load which is carried 40 upon the stationary ends.

The object of my present invention is, therefore, to provide a car of the general service type, which, while having the desirable feature of discharging substantially 45 the entire load, will at the same time possess the necessary strength for the resisting of racking strains and also to provide a construction by means of which the floor of the car may be considerably lowered, making it 50 possible to increase the carrying capacity of the car without increasing its length.

In accomplishing these objects, I have provided a car of this type with a rigid stationary floor extending inwardly from the

end sill and sloping downwardly and outwardly toward the sides of the car. This rigid floor portion may extend inwardly to such distance as may be desirable so as to connect to underframe members of the car, such as the bolster or an adjacent cross member, forming at the same time a discharging floor from which dumpable material may readily be unloaded. The remainder of the floor between these rigid portions I form as usual of drop doors normally 65 substantially horizontal and substantially in the plane with the center sill to form therewith a continuous level floor.

The invention will be further understood by reference to the following specification 70 and drawings, in which—

Figure 1 is a fragmentary side elevation of a general service car embodying my invention;

Fig. 2 is a fragmentary plan view of the 75 same car;

Fig. 3 is an end elevation of the same car;

Fig. 4 is a transverse sectional view of the same car, the section being taken over one of the trucks;

Fig. 5 is a fragmentary plan view of a 80 general service car embodying a modified floor structure over the trucks; and,

Fig. 6 is a transverse sectional view of a general service car showing a further modified form of floor.

As is well known, a general service car may be used for carrying dumpable material one day, and for carrying non-dumpable material, such as lumber and the like, another 90 day. As stated above, heretofore it sometimes has been the practice to provide general service cars with a horizontal flat bottom floor in a single plane and including pivotally mounted dump doors largely or entirely throughout the length of the car. With such construction it is necessary that the floor of the car be at a relatively high level in order that the floor doors over the trucks might be moved into an open position 100 for dumping a dumpable load to the sides of the car. The carrying capacity of the general service car can be increased effectively if the floor of the car over the trucks is lowered, and the car be made self-cleaning if these floor portions are made to slope downwardly and outwardly toward the sides of the car, the stiffness and rigidity of the

car at the same time being maintained at a maximum.

To this end I have provided a general service car having a body 10, including sides 5 11, ends 12, and a single floor, the end portions 13 of which over the trucks preferably are A-shaped, including rigid stationary portions 14 which, as shown in Figs. 1 to 5, inclusive, extend from the center of the car 10 at the level of the top of the center sill 15' downwardly and outwardly toward the sides of the car. The discharge openings between the lower edges of the sides 11 of the car and the outer edges of the sloping 15 stationary floor members 14, normally are closed by side dump doors 15 which may be operated in any suitable manner, such as operating shafts 16 and chains 17 connecting said shafts with the lower edges of said 20 doors 15.

By referring to Fig. 1 of the drawings, it will be noted that the stationary A-shaped floor portion 13 over the trucks at each end extends inwardly from the end sill 27 to the 25 bolster 18 and is connected to the underframe members to stiffen the car. However, if desired, the stationary A-shaped floor portion 13 may extend the full length of the truck to an adjacent cross member 28, as shown in 30 Fig. 5, in which event the side dump doors will extend the same length. By giving the floor portions over the truck of the general service car an A-shaped construction, the effective carrying capacity of the car is effectively increased, the car made self-cleaning, and at the same time because of the rigid connection of these floor portions to the cross 35 members the stiffness and rigidity of the car body is maintained at a maximum without 40 the use of an abnormally heavy and expensive underframe structure.

The floor intermediate the trucks comprises dump doors 19 which are pivotally connected along the center sill and normally 45 being in a horizontal position in the same plane with the upper surface of the center sill to provide a flat bottom. These dump doors 19 preferably are arranged to swing downwardly and inwardly away from the 50 sides of the car for dumping the load outwardly with respect to the track. The operating mechanism for the floor doors 19 may include operating shafts 21 and suitable chains 22 connecting said shafts with said 55 doors. The doors 19 when in their normal horizontal position, not only are suitable for supporting a dumpable load, but also a non-dumpable load, such as lumber and the like. The sloping floor portions over the trucks 60 may receive and hold any of the usual material shipped in the gondola or other flat bottom type of car.

In Fig. 6 I have shown a modified form of construction in which the floor is set at a 65 lower level than shown in the other figures of

the drawings, the sides 11 of the car being correspondingly deepened, and in which the stationary sloping portions 23 do not extend at the same angle to the center of the car, it being noted that the sloping portions 23 are 70 connected by a horizontally arranged floor portion 24. Associated with the floor portions 23 are the side dump doors 25, which are operated in the same manner as described in connection with the other figures of the 75 drawings. The horizontally arranged floor doors 26 intermediate the trucks are also controlled by the same operating mechanism referred to in connection with the other figures of the drawings. The modification provides 80 an arrangement in which the capacity of the car is increased an additional amount. It will be noted in all the forms shown that the floor portions over the trucks extend to a level lower than the floor portion intermediate 85 the trucks.

By means of my invention I have provided a general service railway car in which the sloping floor portions over the trucks make the car self-cleaning, or substantially so, increase the capacity of the car, and give the car a stiff and rigid construction capable of resisting effectively the racking strains occurring in regular service without the use of a heavy and expensive underframe, and at the 90 same time providing a car suitable for carrying in an approved manner dumpable and non-dumpable loads.

It is my intention to cover all modifications of the invention falling within the 100 spirit and scope of the following claims.

I claim:

1. A car of the class described having the usual underframe comprising longitudinal and transverse members and a floor, said 105 floor at the ends of the car comprising stationary portions sloping downwardly and outwardly toward the sides of the car, said stationary portions being disposed below the upper level of the longitudinal and transverse members and being rigidly connected to adjacent transverse members, the remainder of the floor being substantially horizontal and in a single plane and composed largely of doors arranged to discharge the 110 load.

2. A car of the class described having the usual underframe comprising longitudinal and transverse members and a single floor, the floor between adjacent transverse members at the end of the car being formed with downwardly and outwardly sloping portions extending between said transverse members and rigidly connected thereto, the floor between the remaining transverse members being substantially horizontal and composed of doors hinged at or near the center sill and dropping away from the sides of the car to discharge the load.

3. A car of the class described, having a 130

single floor which comprises stationary downwardly and outwardly sloping end portions extending inwardly from the end sills and being connected to the underframe members 5 to stiffen the car, the remainder of the floor being substantially horizontal and substantially in the plane of the top of the center sill.

4. In a general service railway car, a car 10 body having sides, ends and a single floor, the floor over the trucks comprising stationary portions extending downwardly and outwardly toward the sides of the car between adjacent cross members and being rigidly connected thereto, and side dump doors 15 extending between the lower edges of the sides of the car and the outer edges of the stationary portions, the floor between the trucks comprising pivotally mounted doors normally in a substantially horizontal plane

and above portions of the floor over the trucks.

5. A car of the class described having the usual underframe comprising longitudinal and transverse members and a single floor, 25 the floor between adjacent transverse members at the end of the car being formed with downwardly and outwardly sloping portions extending between said transverse members and rigidly connected thereto, the floor between the remaining transverse members being substantially horizontal and composed of doors hinged at or near the center sill and dropping away from the sides of the car to discharge the load, and operating mechanism for said doors. 30

Signed at Chicago, Illinois, this 10th day of October, 1918.

HARRY S. HART.
